UNITED STATES PATENT OFFICE.

ABRAHAM MEGIBOW, OF WEST NEW YORK, NEW JERSEY.

DESIGN FOR LACE.

60,254.

Specification for Design. Patented Jan. 17, 1922.

Application filed October 12, 1920 Serial No. 416,555. Term of patent 3½ years.

To all whom it may concern:

Be it known that I, ABRAHAM MEGIBOW, a citizen of Russia, residing at West New York, county of Hudson, and State of New Jersey, have invented a new, original, and ornamental Design for Lace, of which the following is a specification, reference being had to the accompanying drawing, forming a part thereof.

The drawing illustrates a plan view of my ornamental design for lace, three repeats being illustrated.

I claim:

The ornamental design for lace, as shown.

ABRAHAM MEGIBOW.
